LIQUID SCALE

William P. Feeney, Mosinee, Wis.

Application October 16, 1933, Serial No. 693,723

4 Claims. (Cl. 92—46)

This invention relates in general to improvements in regulators and more particularly to stock regulators for paper making machines and the like. In my Patents Nos. 1,134,831, 1,143,523, 5 1,331,057 and 1,763,691, I have shown certain types and improvements in stock regulators for paper making machines. This invention relates to certain improvements on these inventions and other improvements not disclosed in any of the 10 above patents.

Previously there have been encountered certain difficulties in the operation of stock regulators such as the permitting of stratification of pulp whereby settling takes place allowing a variation 15 in density of the stock fed to the paper making machine. Also there has been a certain lag in the reaction of the control mechanism to changes in volume or characteristics of the feed stock.

One of the primary objects of my invention is 20 to overcome these disadvantages and particularly to provide a more sensitive control device for the regulating of the flow of stock.

With the foregoing and other objects in view the invention consists in the combination of parts 25 and in the details of construction hereinafter set forth in the following description and appended claims, certain embodiments thereof being illustrated in the accompanying drawing in which:

Figure 1 is a view in side elevation partly in 30 section of the device;

Figure 2 is a view in section taken along line 2—2 of Figure 1;

Figure 3 is a view in section taken along line 3—3 of Figure 1; and

Figure 4 is a view in section taken along line 4—4 of Figure 1.

Referring more particularly to the drawing my device consists in a stock regulator which may be a box of wood or metal and which is divided into 40 three sections, 1, 2 and 3, by means of suitable partitions 2' and 3'. The material to be weighed or regulated may be pumped or otherwise conveyed in compartment 2 through inlet pipe 25. The partition 3' may terminate at its upper extremity below the level of the box and there is provided a gate 4 for regulating the overflow from compartment 2 into compartment 3 over the top of the partition. Arranged exteriorly of the box above compartment 3 are a pair of bearing members 5 and 6 to receive a shaft 7 which has secured thereto an adjustment plate 8. This shaft also has secured thereto an arm 9 which is adapted to receive a weight 10 slidably thereon, the weight being provided with a tightening nut 11 so that the weight may be secured

on the arm at any desired point. The weight 10 is preferably set so that when the stock rises to within two or three inches of the top of the compartment 2 the gate 4 will be opened by pressure and the stock will flow back to the source of supply from compartment 3. The pressure necessary to overcome the closing effect of the weight and the arm 9 on the gate 4 is naturally controlled by the position of the weight on the arm. When the overflow gate once starts to open, the 65 pressure necessary to continue this opening operation becomes less as the arm and the weight approach a vertical position so that when it reaches a vertical position no pressure at all will be required to keep the gate open. In the reverse 70 operation as the stock becomes too thin or light in weight or there is less of it delivered to compartment 2 and the gate starts to close, it will close with increasing pressure as the weight will be becoming further off center of the bearings. 75 Contrary to the usual practice the regulating device being located entirely exteriorly of the box the bearings 5 and 6 are preferably of the ball or roller type and may be lubricated with oil rather than grease so as to make them as sensitive as 80 possible.

From compartment 1 the stock passes through the outlet 26 into the paper making machine.

The outlet from compartment 2 to compartment 1 is provided with a hand operated gate 12, the gate being connected at 13 to a worm 14 operated by means of a hand wheel 15. This gate works from the bottom up in guide members 24 to adjust for the amount of stock required. There is also arranged another gate 16 pivoted at 17 to a partition 3' for releasing the stock in compartment 2 so that it may flow through to compartment 3 and the outlet 27 and back to the chest or source of supply. This gate is to be used when it is desired to stop the flow 95 of stock without stopping the pump. Integral with gate 16 is an arm 18, the weight of which tends to keep gate 16 closed. In order to keep the gate 16 closed there may be provided a suitable catch 19 for engaging the arm 18 to maintain the gate 16 closed. 100

In connection with the operation of the overflow gate 4 it has been found in actual practice with the conventional type of regulator that if it required one pound of pressure to open the gate 105 one inch, it would require more pressure to open it an inch and a half and still more to open it two inches. In the present device, however, the necessary pressure to continue the opening operation becomes less and less as the gate swings 110

open. The compartment 2 is preferably on a slight angle towards compartment 3 so that starting at the bottom of gate 4 this will allow the gate to be maintained more in line with the arm 9. Furthermore, the tank is narrow and just as wide as the pipe that furnishes the supply so that the stock in compartment 2 will travel at the same speed when it leaves this compartment as it was travelling when it entered. This will 10 not allow water to settle out and leave the thick stock on top.

In order to effect a connection between the gate 4 and the shaft 7 I have shown an arm 20 secured at 21 to the gate and terminating at its 15 other end in a collar 22 through which the shaft 7 passes. The collar is fixed to the shaft so as to rotate therewith when actuated by the weight 10. Instead of having the partition 3' terminate below the top of the other partition and end 20 walls as previously suggested, I have actually shown in the drawing the partition 3' recessed at 23 and formed the gate 4 so as to be adapted to regulate the overflow through the recess.

As previously stated my device is sensitive to 25 changes in density of the stock. Thus if the stock becomes thick the added weight tends to open the gate 4 and pass the stock into the overflow compartment 3 and out the outlet 27 so that a certain amount of the heavy stock will be 30 recycled. In this manner the amount of solids to the paper machine may be controlled.

By means of the improvements above described, stratification in the supply compartment 2 is eliminated and there is always circulation in 35 this compartment. There is no variation in the density of the stock which passes out of compartment 1 into the paper making machine.

I claim:

1. A stock regulator comprising an inlet compartment, an outlet compartment, and an overflow compartment, a passageway from said inlet compartment to said overflow compartment, said passageway being regulated by a gate, said gate being controlled by means responsive to pressure 40 within the inlet compartment with decreasing resistance to said pressure as the opening operation of said gate continues from a closed position to a substantially fully open one.

2. A stock regulator comprising an inlet compartment, an outlet compartment, and an overflow compartment, a passageway from said inlet compartment to said overflow compartment, said passageway being regulated by a gate, said gate being controlled by means responsive to pressure within the inlet compartment with decreasing resistance to said pressure as the opening operation of said gate continues from a closed position to a substantially fully open one, said means comprising a weight-operated arm connected to said gate.

3. A stock regulator comprising an inlet compartment, an outlet compartment, and an overflow compartment, a passageway from said inlet compartment to said overflow compartment, said passageway being regulated by a gate, said gate being controlled by means responsive to pressure within the inlet compartment with decreasing resistance to said pressure as the opening operation of said gate continues from a closed position to a substantially fully open one, said gate being disposed in closed position, at an angle to the vertical and being provided with a weight-operated arm connected thereto for determining the amount of pressure necessary to effect a flow through said passageway past said gate.

4. A stock regulator comprising an inlet compartment, an outlet compartment, and an overflow compartment, a passageway from said inlet compartment to said overflow compartment, said passageway being regulated by a gate, said gate being controlled by means responsive to pressure within the inlet compartment with decreasing resistance to said pressure as the opening operation of said gate continues from a closed position to a fully open one, said gate being disposed in closed position at an angle to the vertical and being provided with a weight-operated arm connected thereto and arranged so that the resistance set up by the said weight to the opening of the gate will become lessened as long as the opening operation of said gate continues, said weight being adjustably carried by said arm.

WILLIAM P. FEENEY.
